SOAP-DISPENSING MACHINE.

1,219,364.

Specification of Letters Patent. Patented Mar. 13, 1917.

Application filed March 11, 1915. Serial No. 13,731.

To all whom it may concern:

Be it known that I, ANTHONY GEORGE WISE, a citizen of the United States, residing at Minneapolis, in the county of Hennepin and State of Minnesota, have invented a new and useful Soap-Dispensing Machine, of which the following is a specification.

My invention relates to improvements in soap dispensers in which a liquid soap is carried in a suitable container, and fed out by the operation of a plunger or piston which may be operated either manually or by means of a foot lever.

One of the objects of my invention is to allow the liquid soap to be fed down by gravity to a chamber in which the plunger operates, and allow the plunger to carry, by means of a spring pressure, a predetermined amount of liquid soap and force it to the outside of the dispenser, where it can be caught by the hand of the person using the dispenser.

Another object of my invention is to provide means whereby the definite amount of soap delivered, when the dispenser is operated, can be varied to suit the idea of the person owning or operating the dispenser.

Another object of my invention is to provide means whereby the liquid soap will be fed down not only by gravity, but on account of a vacuum established in the dispenser.

Another object of my invention is to allow the retaining cap, carrying the nozzle and retaining valve, to be detached so the parts may be cleaned, and by letting the plunger down to the full length of its stroke, when the retaining cap is detached, allow the entire machine to be flushed.

I attain these objects by the mechanism illustrated in the accompanying drawing in which—

Figure 1 is a vertical section of the entire machine.

Fig. 2 is a section through the line A—A.

Fig. 3 is a section through the longitudinal axis of the plunger and retaining valve.

Similar letters and similar figures refer to similar parts throughout.

A bracket 1, preferably of cast iron, suitably secured to a wall or other support 2' by bolts 2" has formed on one extremity thereof an arm provided with an opening or channel 25 adapted to receive within the threaded end 25' thereof a hollow threaded

plug 2 carried by the container 3. Gaskets 4 and 5 render the joints liquid proof, as best illustrated in Fig. 1.

A retaining cap 6 when screwed on to the threaded extension 26 of the enlargement 2", serves as a nozzle for dispensing the liquid soap and also incloses a valve 7, a spring 8, and retainer washer 9. The cap, when removed, can be thoroughly cleaned without allowing the liquid soap in the container to run out and be wasted. Flutes or channels 27 are provided in the interior walls of the cap as shown in Fig. 2, for the purpose of allowing the liquid soap to pass the valve 7 and washer 9 when the dispenser is operated.

A plunger stem 10 snugly fits and is mounted for reciprocation within the opening 28 formed in the enlargement 2", the lower end of which opening communicates with the chamber 17 which in turn communicates with the opening 25. A piston valve 29 of ordinary construction is carried on the lower extremity of the plunger stem. A pin 11 and a washer 12 maintain a slidable connection between the outer extremities of the stem 10 and a bell crank lever 13 pivoted to the arm 1 at 14, so the valve 29 may be operated by means of the said bell crank.

The bell crank 13 may be operated manually, or it may be connected by a chain 15 to the pivoted lever 16 so as to allow it to be operated by the foot.

An aperture 21 is so located in part 1, that when a pin (not shown), is inserted therein, the bell crank 13 is held in such position that the piston end of stem 10 remains in the chamber 17 thereby permitting the retaining cap 6 to be removed for cleaning, without allowing the liquid in the container 3 to run out. If the pin is withdrawn from the hole 21 when the retaining cap is removed, the piston head 29 will be forced outside of the chamber 17 by the spring 18, so the liquid soap will run freely out of the container 3 and the entire machine may be flushed.

When the plunger is operated, the first motion is upward; the retaining valve 7 seats itself and the continuing motion of the piston head of the plunger creates a partial vacuum in the lower part of the chamber 17, thus the liquid soap is fed into the chamber when the piston opens it to communication with the channel or inlet 25, not

only by gravity, but by suction due to said partial vacuum, atmospheric pressure being maintained through the aperture 20.

It will be seen that when the plunger is drawn upward by means of the bell crank 13, the valve 7 seats itself against the seat 30 under the action of the spring 8, which abuts on one end against the valve 7 and on the other end against the washer 9 carried by the cap 6, and the other end 7' of the valve 7, which is larger than the aperture 19 and normally closes the same, opens the aperture 19 in the cap 6; this aperture preferably being small enough to prevent the liquid soap from running therefrom without the soap being under pressure, so that any soap that might be in the cap 6 would not trickle out of the aperture 19 during the upward travel of the plunger. When the plunger is returned by the spring 18 the valve 7 will be forced from its seat by pressure of the liquid carried downward by the plunger, the liquid soap will be forced through the channels 27 in the cap 6, as better shown in Fig. 2 and out through the aperture 19 until the aperture is closed by the end of the valve 7, when the plunger head 29 forces the valve into its normal position. It is evident therefore that the stem 7' of the valve 7 serves two purposes. One is its action as a valve, which prevents escape of liquid when the parts are as shown in Fig. 1, and the other is to serve as a stop to limit the motion of the valve 7, both functions, however, being performed simultaneously.

The operation as described shows that a definite amount of liquid soap will be fed to the chamber 17 after the plunger is drawn upward, and this definite amount of soap will then be forced past the valve 7 to the interior of the cap 6 and out through the nozzle 19 upon the return of plunger 10 to its normal position.

In Fig. No. 3 I have shown a means whereby the definite amount of soap delivered with each stroke of the plunger, may be varied to suit the purposes of the party owning or operating the soap machine.

In this figure the numeral 23 designates a hole drilled and tapped in the piston valve 29 and stem 10, to snugly receive the headless screw 22, the end of which is normally flush with the face of the piston 29. The operation as described was with the screw 22 turned into the piston 29 so the head was flush or below the surface of the piston head.

If, however, this screw 22 is withdrawn so the slotted end of the screw projects from the piston head of the plunger, the normal position of the piston head of the plunger will be determined by the screw and the piston head spaced from the head 7 the distance that the screw has been turned out of the piston. As the piston then will not de-

scend as far as when the screw is turned flush with the piston head, less soap will be forced out at each operation.

Hence, by screwing out this small screw, the amount of soap delivered at each stroke of the plunger is lessened.

The container 3 may be covered with any suitable cover such as 4' which may be locked in position by any suitable means such as 5'. The cover is preferably provided with an opening 20, the function of which has been hereinbefore explained.

While in this specification the word "soap" or "liquid soap" is used to describe the liquid carried in the container 3, the machine may be used for other liquids, and I do not limit myself to an apparatus for dispensing soap.

I am aware that prior to my invention, soap dispensers have been made with various types of plunger mechanisms operating in conjunction with a soap container. I therefore do not claim such a combination broadly, but

I claim:

1. In a soap dispenser, the combination of a container, a mounting for said container having a chamber therein and a communication between said chamber and said container, a piston slidable in said chamber, a retaining valve seatable at the bottom of said chamber, a spring normally pressing said retaining valve toward said seat, a cap surrounding said retaining valve, an orifice at the bottom of said cap closable by said stem when said valve is fully depressed against the tension of said spring by said piston.

2. In a soap dispenser, the combination of a container having a support for said container, a chamber in said support and an opening leading from said chamber to said container, a piston reciprocally mounted in said chamber, a cap associated with said support at one end of said chamber, a retaining valve reciprocally mounted in said cap and a stem on said retaining valve, an orifice in said cap adapted to be closed by said stem when said retaining valve is in its normal position, flutes along the walls of said cap, a spring normally holding said plunger against said retaining valve and said stem in position to close said orifice, and a retaining valve spring adapted to seat said valve and open said orifice when said plunger is raised.

3. The combination in a soap dispenser of a container having a support for said container, a chamber in said support and an opening leading from said chamber to said container, a plunger reciprocally mounted in said chamber, an adjusting screw in the bottom of said plunger, a cap positioned on said support at one end of said chamber, a retaining valve having a stem reciprocally

- mounted in said cap, a seat for said valve at one end of said chamber, an orifice in said cap adapted to be closed by the stem of said valve in one position of said valve, a spring 5 associated with said valve adapted to hold said stem away from said orifice when said plunger is elevated, a spring associated with said plunger adapted to normally press said plunger against said retaining valve and 10 close said orifice against the tension of the retaining valve spring, an adjusting screw in said plunger for varying the reciprocal relations of said plunger and said valve, and flutes in the wall of said cap, whereby communication is opened between the part of 15 said cap below said retaining valve and that above said retaining valve when said valve is lifted from its seat.
4. In a soap dispenser, the combination of 20 a container, a mounting for said container having a chamber, a plunger having a piston head at one end operated by means of a bell crank at the other end, a spring normally holding the plunger at the lower end of its 25 stroke, a valve, a stem on said retaining
- valve, a spring normally holding said valve against the piston head of said plunger and capable of closing said valve on its seat when said plunger is withdrawn, a cap containing said valve and said spring and attached to 30 the mounting for the container, and having its sides fluted and having at one end a nozzle opening.
5. In a soap dispenser, a container, a mounting, means for connecting said container to said mounting, a chamber in said mounting, a plunger in said chamber held in normal position by a spring and operable by means of a bell crank, a cap attached to said mounting, a retaining valve, a spring capable of seating said valve in said mounting, said cap having its sides fluted and having at its lower extremity a nozzle opening, said plunger controlling the normal position of 35 40 said valve.
